UNITED STATES PATENT OFFICE

CHARLES W. MCKINLEY, OF FLINT, MICHIGAN, ASSIGNOR TO A C SPARK PLUG COMPANY, OF FLINT, MICHIGAN, A COMPANY OF MICHIGAN

INSTRUMENT-PANEL MOUNTING

Application filed November 14, 1927. Serial No. 233,181.

This invention relates to an instrument panel and more particularly to a panel of the type ordinarily mounted on the dashboard of an automotive vehicle.

- 5 It is an object of this invention to provide an improved instrument panel mounting which can be more cheaply manufactured and more readily and easily assembled than those now in use.
- 10 Other objects and advantages of the invention will appear in the course of the following description, taken in connection with the accompanying drawing and appended claims.

15 In the drawing:

Figure 1 is a front view.

Figure 2 is a section on the line 2—2 of Figure 1.

20 Figures 3 and 4 are sectional views illustrating modified forms of my invention.

Referring to the drawing, I have illustrated a part of a dashboard or instrument board of an automotive vehicle which comprises a comparatively thin strip 10 provided 25 with an aperture shaped to fit the periphery of the bezel 12. The bezel in the present case is made up in half sections from cold rolled stock and may be one of a variety of shapes in section, as will appear from a comparison 30 of Figures 2, 3 and 4. The bezel is shown as shaped on its inner side to provide a peripheral slot within which is adapted to fit the instrument supporting plate or panel 14, which is provided with apertures 16 which 35 may be of any suitable shape, size and arrangement, depending on the character of the instruments mounted thereon. While the instruments may be fastened to the panel in any desired manner the described construction being such as to assure the retention 40 of said panel in said bezel so long as the latter remains in the aperture in strip 10, or its equivalent, I have illustrated the instruments 18 as fitting against the panel from the rear side and held thereon by means including a

U-shaped clamping or compression element 20. This may be fixed to the strip 10 by means of screws 22 welded or otherwise fixed thereto, said U-shaped element being preferably secured to the panel 14 by means such as a tension screw 24 fixed to the rear side of the panel. The instruments 18 are shown as held in place by set screws 24 threaded in the clamp 20 and provided with winged heads 26; and it will be seen that removal of 50 the bezel 12 from the aperture in strip 10 (as permitted by a backing-off of the nut shown upon the end of the screw 24) permits a direct removal of the panel 14 from the slots in the sections comprising bezel 12, and an 55 incidental disassembly of all mentioned parts.

I claim:

1. In an instrument supporting assembly, a supporting strip provided with an aperture, a bezel fitting in said aperture and provided with a peripheral shoulder on one side and a peripheral slot on the other, an apertured instrument panel supported in said slot, and means for holding said panel and bezel against displacement from said supporting 65 strip, mentioned parts assuring the retention of said panel in said slot so long as said bezel remains in said aperture and otherwise permitting direct separation thereof.

2. In an instrument supporting assembly, 70 a supporting strip provided with an aperture, a bezel fitting in said aperture and provided with a peripheral shoulder on one side and a peripheral slot on the other, said bezel being formed in a plurality of sections, an apertured instrument panel supported in said slot, and means for holding said panel and bezel against displacement from said supporting strip.

3. In an instrument supporting assembly; 75 a strip provided with an aperture; a panel; a sectional panel-receiving bezel whose sections are adapted, when assembled, to interfit within said aperture,—said sections being 80 provided with means effective for the retention 85 of said panel in said slot so long as said bezel remains in said aperture and otherwise permitting direct separation thereof.

tion of said panel by said bezel so long as the latter is held within said aperture; and means for so holding said bezel.

4. An instrument-supporting assembly as defined in claim 3, in which said holding means includes a substantially U-shaped compression element engaging said strip and a tension element connecting said panel and said U-shaped element.

10 In testimony whereof I affix my signature.
CHARLES W. McKINLEY.
